CARTON OPENING MACHINE

Edward J. Derderian, 2514 N. Wilson, Fresno, Calif.

Filed Sept. 23, 1958, Ser. No. 762,781

12 Claims. (Cl. 93—53)

The present invention relates to a carton opening machine and more particularly to an apparatus for mechanically opening boxes of foldable sheet material from a flat folded condition to a substantially rectangular open condition.

The boxes with which the present invention is concerned are of foldable sheet material usually made of cardboard, fiberboard, or other foldable sheet material, hereinafter generically referred to as "paperboard" for descriptive convenience. Such boxes are normally formed in manufacture so as to provide opposite end and side walls interconnected along fold lines defining corners for the box and to provide upper and lower opposite end and side flaps respectively connected along fold lines to the end and side walls but not connected to each other. For shipping, storing, stacking, and the like, such boxes are normally folded in flat condition. In such condition, a box is usually folded along diagonally related corner fold lines with the flaps open to bring an adjacent end and side wall into opposed contact with the other end and side wall and likewise to bring the respective upper and lower flaps into contact.

In order to fill the box, such as in a packing operation, it is necessary first to unfold the box into open, substantially rectangular condition. Next, the bottom end and side flaps are usually folded into overlapping relation prior to filling, and the top end and side flaps overlapped subsequent to filling. Thereafter, the end and side flaps are sealed in place. In the past the preliminary unfolding step has been performed largely by hand. It is obviously a time consuming, laborious, and expensive task. Although machines have been devised prior to the subject invention for mechanically unfolding such boxes, they have been relatively more complex and expensive than desirable. Further, the known prior art in this field has generally consisted of precision machines which have required considerable care and attention to operate, maintain, and repair.

Accordingly, it is an object of the present invention to provide a machine for mechanically opening boxes of foldable sheet material from a flat folded condition into a substantially rectangular open position.

Another object is to provide an economical box opening machine.

Another object is to provide a box opening machine which is simple to operate, maintain, repair, and the like.

Another object is to provide a box opening machine containing a minimum of precision parts thereby requiring less care and attention to operate than the machines of the prior art in this field.

Another object is to provide a box opening machine which does not damage a box during the opening operation.

Another object is to provide a machine of the nature described which opens boxes in rapid succession and with complete dependability.

Another object is to provide a box opening machine

2

which operates continuously with a minimum of interruption as long as boxes are supplied to the machine.

These, together with other objects, will become more fully apparent upon reference to the following description and accompanying drawings.

In the drawings:

Fig. 1 is a top plan view of a box opening machine embodying the principles of the present invention showing a plurality of boxes in full lines being supplied to the machine, showing a box in double dashed lines in partially open condition, and showing a box in single dashed lines in fully open condition.

Fig. 2 is a longitudinal vertical section taken on line 2—2 of Fig. 1.

Fig. 3 is a somewhat enlarged fragmentary transverse vertical section taken on line 3—3 of Fig. 1.

Fig. 4 is a somewhat enlarged fragmentary plan view of a portion of the machine, as seen in Fig. 2, but with a box shown therein in cross section in partially unfolded condition just prior to the partially open condition shown in double dashed lines in Fig. 1.

Fig. 5 is a view similar to Fig. 4 taken on line 5—5 in Fig. 2 with the feeding mechanism omitted and showing a folded box in an initial stage of unfolding in advance of that shown in Fig. 4.

Fig. 6 is a view similar to Fig. 5 but showing the box in a stage of the opening procedure subsequent to that in Fig. 5 but in advance of that in Fig. 4.

Fig. 7 is a view similar to Fig. 6 but showing the condition of the box subsequent to that in Fig. 4 but in advance of the double dashed line position indicated in Fig. 1.

Fig. 8 is a somewhat enlarged fragmentary transverse vertical section taken on line 8—8 of Fig. 2.

Fig. 9 is a somewhat enlarged perspective view of a portion of a box supporting panel and a detail of a box opening wedge employed in the subject invention.

Fig. 10 is a plan view of the wedge and mounting structure of Fig. 9.

Fig. 11 is a perspective view of a box of the type adapted to be opened by the machine of the subject invention showing the box in unfolded open condition.

Referring more particularly to the drawings, the machine of the subject invention includes an elongated support frame 15, best seen in Fig. 1. The frame has a pair of substantially horizontal L-shaped longitudinal side members 16 having aligned main portions 17 in spaced relation and transversely outwardly extended spaced parallel horizontal portions 18. A substantially straight longitudinal side member 20 extends in spaced parallel relation to the main portions of the side members 16. Both of the side members have horizontal flanges 21 and downwardly extended vertical flanges 22. Suitable bracing, as 23, transversely rigidly interconnects the side members of the support frame. No special emphasis is to be placed on the precise frame illustrated and described inasmuch as it will be apparent as the description proceeds that the support frame can have many forms suitable for supporting the parts of the subject machine.

With continued reference to Fig. 1, a pair of substantially horizontal elongated outer angulated box supporting sides 29 and 30 are supported in the frame 15 in parallel relation to and between the horizontal portions 18 of the side frame members 16. The outer slides have horizontal and vertical flanges. Additionally, intermediate slides 31 are supported in substantially horizontal coplanar relation with the outer slides. With reference to Fig. 2, blocks 32 and 33 rigidly transversely interconnect adjacent outer and intermediate slides. An elongated slide adjusting screw 34 provides an inner end rotatably mounted in the block 32 and an outer end journaled in the support frame. The screw has threads

65

intermediate its ends which are screw-threadably extended through the block 33. By rotating the screw, it will be evident that the blocks and their corresponding slides are transversely adjusted relative to each other.

An elongated generally rectangular box guiding plate 40 is rigidly mounted in the frame 15 in vertical position and longitudinally extended in substantially parallel relation between the side members 17 and 20. The guiding plate is positioned opposite to the space between the auxiliary portions 18 of the L-shaped side members 17 in right-angular relation to the slides 28, 30 and 31, as best seen in Fig. 1. The guiding plate has a lower edge 42 in adjacent spaced relation to the slides, an upper edge 41, and an elongated slot 43 extended longitudinally of the plate substantially parallel to and between the upper and lower edges, as best seen in Fig. 2. For purposes subsequently to be apparent, the plate is cut away at one end thereof providing a notch 44. For purposes of convenient subsequent reference, the support frame 15 is regarded as having a forward end portion 46 and a rearward end portion 47.

Front and rear wings 52 and 53 rigidly extend in perpendicular relation from the opposite ends of the guiding plate 40 toward the side member 20, it being noted that the rear wing extends downwardly below the lower edge 42 of the guiding plate whereas the front wing terminates along the upper edge of the notch 44, all as best seen in Fig. 2. A substantially horizontal gusset plate 55 rigidly interconnects the upper edges of the guiding plate and the front wing, and a bridging member 56 rigidly interconnects the upper and lower portions of the guiding plate to impart rigidity thereto.

With attention being directed to Fig. 1, an elongated presser mounting shaft 60 provides opposite ends 61 mounted in tracks, not shown, in the auxiliary frame portions 18 for slidable movement longitudinally of and above the slides 29, 30 and 31. A carriage 62 is longitudinally slidably mounted on the shaft, and a U-shaped box presser 63 is pivoted for horizontal swinging movement on the carriage. The presser includes a pair of spaced parallel presser arms 64 extended toward the guiding plate 40.

Tension springs 73 interconnect the frame 15 and the opposite ends 61 of the shaft 60 so that the shaft and the presser 63 are yieldably urged toward the guiding plate 40. A supply of boxes 80 is positioned on the slides 29, 30 and 31 in upstanding position between the guiding plate 40 and the presser arms 64. The boxes are in folded condition and the yieldably inwardly urged shaft 60 applies pressure to the supply of boxes tending to urge the innermost box flat against the guiding plate.

For purposes of obtaining a fuller understanding of the present invention, one of the boxes 80 is shown in open condition in Fig. 11 and is presently briefly described. The box includes oppositely disposed side walls 81 and 81' and end walls 82 and 82' interconnected along fold lines defining forward corners 83 and 84 and rearward corners 85 and 86. It is to be noted that the designation of the corners as being forward and rearward is only for descriptive convenience in connection with the operational positions in the subject machine, as will be evident. Each box also provides upper and lower end and side flaps 88 and 89, respectively, connected to the end and side walls along fold lines but not connected to each other. For purposes of loading into the present machine, the boxes are folded along the forward and rearward diagonally related corner fold lines 83 and 85 so as to bring what is hereinafter referred to as the first end and side walls 82 and 81 into contact with the second end and side walls 82' and 81', respectively. Likewise, the associated end and side flaps are brought into contact. It is to be observed that when the box is folded in this manner, and positioned as described on the slides 29, 30 and 31 and against the guiding plate 40, the first end wall is disposed forwardly

of the first side wall. Conversely, the second side wall is disposed forwardly of the second end wall. Otherwise stated, the corner 83 is disposed forwardly of the corner 85 with the forward unfolded corner 84 therebetween and against the plate 40.

As will be seen in Fig. 11, the end walls 82 with their end flaps 88 constitute end panels of the box and the side walls 81 with their side flaps 89 constitute side panels, which panels are successively interconnected in box or carton defining relation and are marginally slotted at their junctures. As evident in Figs. 4 through 7, when folded and pushed along the passage from right to left, they each provide a first end wall folded flatly against a first side wall continuous therewith, a second side wall continuous with the first end wall flatly overlapping the first side wall, and a second end wall continuous with the first side wall folded flatly against the second side wall.

Returning now to a description of the subject machine 20 and referring to Figs. 1 and 2, in particular, pairs of vertically spaced bearings 95 are mounted on the front and rear wings 52 and 53, and front and rear shafts 96 and 97 are journaled in the bearings in substantially vertical positions. Front and rear sprockets 98 are respectively connected to the lower end of the front shaft and to the upper end of the rear shaft in substantially horizontal positions coplanar with each other and with the plane of the slot 43 in the guiding plate 40, as best illustrated in Fig. 2. An elongated endless box feeding chain 99 is extended around the sprockets, and a pair of box feeding dogs 100 having outwardly disposed L-shaped pockets 101 are secured to the chain for movement therewith in a circuitous path through the slot from the rearward end 47 of the frame 15 toward the forward end 46 thereof, and return. During such movement, the pockets of the dogs open forwardly relative to the direction of movement of the dogs. Considering Fig. 1, the dogs divided the chain into two substantially equal lengths. The dogs are positioned so that the rearwardly disposed corner 85 of the innermost box 80 in the supply of boxes fits into the pocket of the dog as it moves forwardly through the slot, as illustrated in dashed lines in Fig. 1. In this manner the dogs successively engage the boxes in the supply thereof and slide them one by one longitudinally along the guiding plate. A driven sprocket 103 is secured to the lower end of the rear shaft 97, and a drive chain 104 extends around the driven sprocket and a drive sprocket, not shown, connected to an engine, or the like, for supplying motive power to the feeding chain.

An upstanding mounting member 110 is secured to the gusset plate 55, as best seen in Fig. 3. A hold-down bar 111, disposed in a substantially horizontal position vertically spaced above and slightly outwardly extended from the upper edge 41 of the guiding plate 40, is elevationally adjustably borne by the mounting member by means of a mounting flange 112 connected to the mounting member. The flange has a vertically disposed slot 113, a bolt 114 is extended through the slot and the mounting member, and nut 115 is releasably tightened onto the bolt. The hold-down bar is elevationally adjustable so as to be in contact or closely adjacent spaced relation to the upper edges of the upper flaps 88 and 89 of the boxes during their longitudinal slidable movement along the guiding plate 40 by the feeding dogs 100. The hold-down bar thus prevents the folded boxes 80 from moving upwardly out of predetermined positions, as best seen in Fig. 2.

As illustrated in Fig. 3, upper rail mounting brackets 70 120 provide horizontal flanges 121 in spaced parallel relation and transversely adjustably connected to the main portion 17 of the forwardly disposed side member 16. Specifically, spacer blocks 122 are interposed the horizontal flanges 121 and 21, elongated slots 123 are provided 75 in the horizontal flanges 121, and bolts 124 are extended

downwardly through the slots and screw-threaded into the spacer blocks. Washers 125 encircle the bolts between their heads and the horizontal flanges of the mounting brackets. The mounting brackets also have inner upwardly disposed vertical flanges 127 in a substantially common plane parallel to the guiding plate 40.

With reference both to Figs. 1 and 3, in particular, an elongated upper box guiding and flap engaging rail 130 is rigidly secured to the vertical flanges 127 of the mounting brackets 120 and has a rearward end edge 131 substantially perpendicular to the guiding plate 40 and in a vertical plane substantially coplanar with the vertical flange of the slide 29. Otherwise stated, the rearward end edge of the upper rail is adapted for engagement or closely adjacent spaced relation to the forwardly disposed corners 83 of the boxes 80 in the supply of boxes. The upper rail also has a longitudinally extended inner side edge 133 disposed in a vertical plane in spaced parallel relation to the guiding plate. The spacing between the inner edge of the rail and the guiding plate is, of course, adjustable by means of the mounting brackets 120 and is adjusted to substantially the same width as the thickness of the boxes 80 in folded condition. Thus, it will be evident that the rearwardly extended end of the upper rail is in forwardly overlapping relation with the guiding plate.

As seen in Figs. 2 and 3, a substantially horizontal main open box supporting panel 140 is rigidly mounted in substantially horizontal position in the frame 15 forwardly of the guiding plate 40 and in substantially the same horizontal plane as the slides 29, 30 and 31. The panel has a rearwardly disposed downturned edge 141 in relatively closely adjacent spaced relation to the slide 29 and a pair of longitudinally extended side edges 142 inwardly spaced from the vertical flanges 22 of the frame members 16 and 20. The support panel is mounted in the frame on legs 143.

A lower main box guiding and flap engaging rail 150 is mounted in vertically spaced substantially parallel relation below the upper rail 130 and above the panel 140 by means of a post 151, forming a part of the support frame 15. The lower main rail has a longitudinally extended inner side edge 152 in the same vertical plane as the side edge 133. Further, an auxiliary lower box guiding rail 154 is mounted in the frame on a post 151 in transversely spaced substantially parallel relation to the main lower rail and provides a longitudinally extended inner edge 155 parallel to the edge 152. An elongated transversely extended rail adjusting screw 156, seen in Fig. 2, screw-threadably interconnects the posts for transversely adjusting the spacing between the main and auxiliary lower rails. It is to be observed at this point that the spacing between the lower rails is adjusted to conform to the width, that is the distance between the side walls 81 and 81', of a box 80 in open condition, as illustrated in single dashed lines in Fig. 1.

Further, from the description thus far, it will be evident that an elongated longitudinally extended box passageway 160 is defined between the upper and lower rails 130 and 150, and the guiding plate 40 and the lower auxiliary rail 154 as opposite sides and with the supporting panel 140 as a bottom. This passageway has a narrow inlet 161 between the rearwardly extended end of the upper rail and the guiding plate adapted slidably to receive a single one of the boxes 80 in folded condition and a wider outlet 162 between the upper and lower rails 130 and 150 and the auxiliary lower rail 154 adapted to receive a box in open condition.

A U-shaped wedge mounting bracket 170 is best illustrated in Fig. 3. This bracket includes a lower horizontal flange 171 having a longitudinally extended slot 172 and overlaying the upper rail 130 in forwardly spaced relation to the inlet 161 of the passageway 160 and thus adjacent to said outlet 162. A bolt 173 is extended downwardly through the slot and screw-threaded into the rail for enabling longitudinal adjustment of the mounting

bracket on the rail. An inner vertical flange 175 extends upwardly, and an outer vertical flange 176 overlaps the inner vertical flange and includes a vertically disposed slot 177 receiving horizontal bolts 178 screw-threaded into the inner flange. Washers 179 are interposed the heads of the bolts 178 and the outer vertical flange 176. An upper horizontal flange 180 including a slot 181 extends inwardly over the passageway 160.

An elongated vertically disposed spindle 190 is downwardly extended through the slot 181 and provides an upper head 191. A nut 192 is screw-threaded on the lower end of the spindle and washers 193 are provided respectively between the head and the horizontal flange 180 and against the nut. An elongated sleeve 194 is positioned between the horizontal flange 180 and the lower washer 193 in circumscribing relation to the spindle. The sleeve is secured to the horizontal flange so as to be rigid therewith. Further, a horizontal limit stud 195 is rigidly radially rearwardly extended from the sleeve adjacent to its lower end.

A triangular-shaped upper box entering wedge 200 is rigidly borne by the spindle 190 at its lower end between the lower washer 193 and the sleeve 194. With particular reference to Figs. 1, 2 and 3, the wedge has a forward convex edge 201, a substantially straight inner edge 202, a concave edge 203, a rearwardly disposed apex 204 and a forwardly disposed outer guide corner 205. Outer and inner stops 206 and 207 are upwardly extended adjacent to the forward edge 201 on opposite sides of the stud 195, as seen in Fig. 3, for engagement therewith so as to limit pivotal movement of the wedge and the spindle 190 relative to the sleeve 194. A torsion spring 209 coiled around the spindle and interconnecting the spindle and the sleeve urges the inner stop 207 into engagement with the stud and thus urges the wedge to rotate in a clockwise direction, as viewed in Fig. 1. The upper wedge is positioned in the outlet 162 of the passageway 160 in forwardly spaced relation to the inlet 161. In what may be termed a normally inoperative position, the forward outer corner 205 of the wedge is substantially aligned with the inlet, or expressed differently, is substantially transversely extended relative to a vertical plane passing through the inlet, as visualized in Fig. 1. When in operative position, in a manner to be described, the wedge is rotated in a counterclockwise direction by a box 80 so as to move the apex 204 toward substantial alignment with the inlet and in a substantially vertical plane with the forward corner 205, which plane is disposed longitudinally in the passageway and is slightly offset from the guiding plate 40, as seen in Fig. 1. In said operative position, the outer stop 206 engages the stud 195 to limit counterclockwise rotation of the wedge.

Referring to Fig. 9, the main panel 140 provides an opening 215 relatively adjacent to the main portion 17 of the L-shaped member 16, and a horizontal auxiliary underpanel 216 is secured to the supporting panel in covering relation to the opening. An elongated mounting member 217 of thickness equal to the main supporting panel is mounted on the auxiliary panel for adjustable movement longitudinally of itself within the opening and having an upper surface substantially coplanar with the upper surface of the supporting panel. The mounting member has a slot 218 through which is extended a bolt 219 for enabling said transverse adjustment and for securing the mounting member in selected positions.

A lower box entering wedge 225, viewed in Figs. 4 through 7, is of substantially the same construction as the upper wedge 200 and thus has similar portions bearing the same numbers as the upper wedge. The lower wedge, however, is mounted for pivotal movement on a vertically disposed stud 226 connected to the mounting member 217 in coaxial relation to the spindle 190. Further, the upper and lower wedges are oriented so that similar parts are in precise vertical alignment. A shoulder 227 is provided on the mounting member under the

lower wedge, and a stop 229 is rigidly downwardly extended from the wedge for engagement with the stop. As with the upper wedge, a spring 230 interconnects the wedge and the mounting member for yieldably urging the wedge in a clockwise direction, as viewed in Fig. 10, for example, to bring the stop 229 into engagement with the shoulder 227. The lower wedge is moved by a box 80 in a similar manner and has positions similar to the upper wedge.

As best seen in Figs. 3 through 7, a box impeding lever 235 is mounted intermediate its ends on a mounting bracket 236 secured to the lower main rail 150 by means of a vertical pivot pin 237 for horizontal pivotal movement between a position with its inner end 238 extended inwardly of the passageway 160 in forwardly spaced relation to the wedges 200 and 225 and a retracted position outwardly of the passageway. The lever has an outer end 239, and an elongated tension spring 240 interconnects the mounting bracket 236 and the lever at said outer end for yieldably urging the lever into its extended position and into engagement with a cushioned limit block 242 secured to the lower main rail. The lever has an angulated inner inwardly disposed pocket 244 facing rearwardly when the lever is in its extended position in the passageway. As will become apparent the lever and spring constitute a resiliently retractable stop for boxes pushed along the passage.

Referring to Figs. 1, 2 and 3, spaced parallel shafts 248, only one of which is illustrated, are journaled in the support frame 15 in substantially horizontal positions extended transversely of the passageway 160 but beneath the supporting panel 140. Sprockets 249 are rigidly secured to the shafts on opposite sides of the panel for rotation with the shaft. Horizontal upwardly disposed angle bars 250 are secured underneath and to the horizontal flanges 21 of the side frame members 16 and 20 adjacent to the forward end 46 of the frame 15 and generally on opposite sides of the supporting panel. A pair of elongated endless chains 251 are individually slidably positioned on the angle bars and extended around the sprockets 248 for movement longitudinally of the side frame members in circuitous paths. Elongated box pushing rods 252 rigidly interconnect the chains by means of webs 253 in transverse relation to the lower rails 150 and 154. The rods are mounted on the chains for movement longitudinally of the outlet 162 of the passageway 160 between the upper rail 130 and the lower rails in relatively closely adjacent spaced relation to the lower rails, as best seen in Fig. 3. The rods move in this manner within the passageway from a position at the rearward end of the passageway to a position forwardly thereof and return underneath the panel.

With particular reference to Fig. 1, an arcuate spring finger 260 of resiliently flexible material provides a rear mounting end 261 rigidly secured to the front wing 52 and a forward box engaging end 262 extended forwardly into the outlet 162 of the box passageway 160 and generally centrally thereof. The forward end of the finger has a rearward offset portion 263.

Operation

The operation of the described embodiment of the subject invention is explained at this point. The machine is initially loaded with a quantity of boxes 80 placed between the presser 63 and the guiding plate 40, as described. The machine is then adjusted in accordance with the size of box being opened to provide the desired width of the inlet and outlet 161 and 162 of the passageway 160. Further, the hold-down bar 111 is adjusted to correspond to the overall height of the unfolded boxes, and the upper wedge 200 is vertically adjusted on the mounting bracket 170 so as to be spaced upwardly from the upper rail 130 and in closely adjacent relation to the upper edge of the upper flaps 88 and 89 of the boxes, as best seen in Fig. 8. In this connection it is to be understood

that the upper and lower wedges 200 and 225 are respectively positioned above and below the upper and lower main rails 130 and 150 and are actually spaced apart by an amount less the overall height of the incoming folded boxes. The rails, on the other hand, are preferably spaced apart by an amount slightly in excess of the height of the end and side walls 81, 81' and 82, 82' of the boxes, all for a purpose to be described.

The box feeding chain 99 and the pusher rod chains 251 are then motivated to travel in their circuitous paths. When one of the feeding dogs 100 reaches the proper position longitudinally in the slot 43, it engages the rearwardly disposed corner 85 of the box 80 against the plate 40 and slides it longitudinally of the plate into the inlet 161 of the passageway 160. The dog engages only one folded box and the inlet receives only one such box. This box is initially slid forwardly into the outlet 162 of the passageway, as best illustrated in Fig. 5, and brought into engagement with the forward corners 205 of the upper and lower wedges 200 and 225. Continued movement of the dog causes the forward corner 83 of the folded box to rotate the upper and lower wedges against the action of the springs 209 and 230 in a counter-clockwise direction by engagement of said forward corner 205 of the box with the outer corners 205 of the wedges. Thus the box is moved into a position between the upper and lower main rails 130 and 150 and the upper and lower wedges, as seen in Figs. 6 and 8. The forward corners 205 and the apices 204 of the wedges engage the first forwardly disposed end flaps 88 of the box, as seen in Figs. 6 and 8, and in cooperation with the rails, which engage the forwardly disposed upper and lower second side flaps 89 below and above the wedges, respectively, bend said forwardly disposed upper and lower flaps outwardly of the passageway with respect to the end and side walls, 82, 82' and 81, 81'. In this regard, it is to be noted that the box pivots the wedges so that their respective forward corners and rear apices are in a vertical plane closer to the vertical plane of the inner edges 133 and 152 of the upper and lower rails than the guiding plate 40. It is for this reason that the upper and lower flaps are bent outwardly as described.

As the box 80 is moved forwardly by the dog 100, the wedges 200 and 225 eventually slide into the box between the first end and side flaps 88 and 89 into contact with the second side flaps 89, as indicated in Figs. 6 and 7. Further, the inwardly disposed forward corners of the wedges engage the first side flaps 89 thereby initiating opening of the box. At the same time as the wedges enter the box, the dog 100 has moved the box forwardly so that the forward corner 83 is fitted into the rearwardly disposed pocket 244 of the box impeding lever 245, as seen in Figs. 4 and 7. The tension on the spring 240 is sufficient to hold the lever in substantially its original position extended into the passageway 160 against the forward urging of the feeding dog so as temporarily to impede further forward movement of said forward corner 83.

However, the box feeding dog 100 continues its circuitous travel and moves around the forward sprocket 98 in a path substantially transversely of the outlet 162 of the passageway 160. The dog, still in engagement with the rearwardly disposed corner 85 of the box 80, moves this rearward corner forwardly and laterally relative to the forward corner 83 and the second, or now outer, side wall 81' into a partially open position, as viewed in double dashed lines in Fig. 1. During this latter movement of the dog, the second outer side wall 81' is held against the upper and lower main rails 130 and 150 not only by the impeding lever 235 but also by continuing engagement of the upper and lower wedges 200 and 225 with the second side wall 81'. To prevent the box from moving back into folded condition after the feeding dog 100 moves out of engagement with said rearward corners 85, as visualized in Fig. 1, the spring finger 260 is provided. The forward end 262 of this finger is disposed so as to

engage the rearward corner 85 and to prevent its movement rearwardly laterally toward the main rail once said rearward corner has been moved forwardly past the forward end of the spring finger.

Immediately after the dog 100 disengages a box 80 in partially open condition, as viewed in Fig. 1, a pushing rod 252 moves upwardly into the outlet 162 of the passageway 160 and into engagement with said rearward corner 85. As the pushing rod is traveled forwardly in the passageway in engagement with a box, it will be evident that it continues to pivot or hinge the end walls 82 and 82' of the box around the fold lines 83 and 86 until the box is in a substantially rectangular open condition, as also seen in single dashed lines in Fig. 1. At this time the pushing rod is brought into full engagement with the second and now rearwardly disposed end wall 82' and pushes the box forwardly in the outlet of the passageway. The pressure against the box by the rod is sufficient to overcome the tension of the spring 240 whereby the impeding lever 235 is moved into retracted position to allow the opened box to travel forwardly in the outlet of the passageway to a succeeding stage of operation with which the present invention is not concerned. The side flaps slide out from under and past the wedges 200 and 225 as will be evident. It is to be observed that the opposite side walls of the box are slid longitudinally in the passageway against the lower rails 150 and 154 which, together with the pushing rod 252, maintain the box in its opened condition.

Of course, as the opened box 80 is being removed from the outlet 162, the other dog 100 is being moved into engagement with a successive box which will be carried through the same steps as the first box, as described above. In this manner the machine continuously opens the folded boxes as long as a supply of such folded boxes is delivered to the machine.

It will be apparent from the foregoing that a machine has been provided for opening a box of foldable sheet material from flat folded condition into substantially rectangular open condition in a highly satisfactory manner. The machine is adapted to open boxes continuously, to handle the boxes gently so as not to damage them, and to minimize need for attention and adjustment. Not only does the machine conserve time and labor but it is considerably less expensive to operate than machines of the prior art provided for similar purposes.

While the carton opening machine has been shown and described as feeding the boxes 80 along a horizontal path and moving said boxes horizontally during the opening operations, it will be clearly evident that the invention may be embodied in a machine operated in any other desired attitude or position. For example, the machine may be turned on its side, as compared with the position shown, so as to feed the collapsed boxes downwardly or upwardly and thence horizontally during opening operations. Other embodiments will readily occur to those skilled in the art, as for example, such as to have a horizontal path of travel for the boxes as they are fed in collapsed condition and an upwardly or downwardly directed path during opening operations.

Although the invention has been herein shown and described in what is conceived to be the most practical and preferred embodiment, it is recognized that departures may be made therefrom within the scope of the invention, which is not to be limited to the details disclosed herein but is to be accorded the full scope of the claims so as to embrace any and all equivalent devices and apparatus.

Having described my invention, what I claim as new and desire to secure by Letters Patent is:

1. In a machine for opening a box of foldable sheet material having opposite side and end walls interconnected in rectangular relation along fold lines defining corners of the box and having upper and lower side and

end flaps respectively connected to the side and end walls but not connected to each other, the box being initially in flat condition folded along the fold lines of diagonally related corners but being unfoldable into open substantially rectangular condition; a support frame; means mounted on the frame defining an elongated substantially horizontally extended box passageway having forward and rearward end portions, a narrow vertically disposed inlet of substantially the same width as a box in folded condition adapted to receive boxes slidably therein with such diagonally related corners disposed forwardly and rearwardly in the passageway, and a wider outlet communicating with the inlet substantially equal in width to that of a box in open condition and adapted slidably to receive such an open box therein, said passageway defining means including a pair of spaced vertically aligned substantially horizontal side rails extended longitudinally and alongside of the passageway; spaced upper and lower substantially vertically aligned wedges supported by the frame and extended into the outlet of the passageway substantially in the plane of the inlet and respectively above and below the rails, the wedges being spaced farther apart than the height of the side and end walls of the box; a box impeding member supported by the frame for movement between a position extended into the passageway on the opposite side of the wedges from the inlet and a position retracted out of the passageway; means connected to the impeding member yieldably urging it into said extended position; box feeding means mounted in the frame for movement in a circuitous path longitudinally of the passageway through the inlet into said outlet, thence a predetermined distance longitudinally and transversely of said outlet, and return, said feeding means engaging the rearwardly disposed corner of a folded box in said inlet and sliding it into said outlet between the rails and wedges whereby the wedges slide inside of the box between the end and side flaps and into engagement with the side wall which is against the rails, said feeding means sliding the forwardly disposed corner of the box into engagement with said impeding member temporarily to impede forward movement of said forwardly disposed corner, said feeding means during its movement transversely of the passageway urging the rearwardly disposed corner toward the forwardly disposed corner of the box partially to unfold the box; and box pushing means mounted in the frame for movement from a position rearwardly of point of maximum longitudinal entry of the box feeding means into the outlet longitudinally forwardly in the outlet of the passageway for engaging the rearwardly disposed corner of the box in said partially unfolded condition and moving it toward said forwardly disposed corner fully to open the box and thereafter sliding the open box forwardly in the outlet past the impeding member and out of engagement with the wedges.

2. The machine of claim 1 wherein the wedges are of substantially triangular shape having rearwardly disposed apices extended toward the inlet of the passageway and outer forward corners extended transversely in the path of travel of a folded box moved through said inlet and being engaged by the forwardly disposed corner of such a box for rotating the wedges whereby said apices and corners are disposed in a common plane spaced from the rails by an amount less than the thickness of a folded box, and means yieldably urging the wedges into positions with said corners disposed transversely in the path of movement of a folded box into the passageway.

3. In a machine for opening a box of foldable sheet material having opposite side and end walls interconnected in rectangular relation along fold lines defining corners and having upper and lower side and end flaps respectively connected to the side and end walls but not connected to each other, the box being unfoldable from a flat condition folded along the fold lines of diagonally related corners to provide substantially coplanar first side and end walls and flaps and substantially coplanar sec-

ond side and end walls and flaps in opposed relation to said first walls and flaps to an open substantially rectangular unfolded condition; an elongated support frame having forward and rearward end portions; an elongated upstanding box guiding plate longitudinally mounted in the rear end portion of the frame having upper and lower edges and an elongated substantially horizontal slot therein intermediate said edges; vertically spaced substantially horizontal elongated main upper and lower flap engaging rails mounted in the forward end portion of the frame in laterally spaced substantially parallel offset relation to the plate, the upper rail having a rear end portion in closely adjacent opposed forwardly overlapping relation to the plate; an auxiliary substantially horizontal lower elongated box engaging rail in transversely spaced parallel relation to the main lower rail, the main and auxiliary rails and the guide plate defining an elongated box passageway having a narrow rear box feeding inlet between said end portion of the upper rail and the guide plate and a relatively wide forward outlet between the main and auxiliary rails; means mounted in the frame for yieldably urging a folded box against the guiding plate with said first end and side walls and flaps against the plate; spaced upper and lower substantially vertically aligned wedges supported by the frame and extended into the outlet of the passageway substantially in the plane of the inlet; a box impeding lever supported by the frame for horizontal pivotal movement between a position extended into the passageway in forwardly spaced relation to the wedges and a position retracted out of the passageway; means connected to the lever yieldably urging it into said extended position; an endless box feeding chain; means mounting the chain for circuitous travel in a substantially horizontal plane coincident with the slot in the plate; a box feeding dog secured to the chain for movement therewith through the slot for engagement with the rearwardly disposed corner of such folded box to slide the box through said inlet and between the wedges and the main rails so that the wedges initially engage and bend said first end flaps outwardly of the passageway so that the wedges slide under said first side flaps into engagement with said second side flaps upon continued movement of the dog, further travel of the dog sliding the box forwardly in the outlet of the passageway until the forwardly disposed corner of the box strikes the lever whereby forward movement of the box is temporarily impeded, still further travel of the dog moving the end walls and said first side wall outwardly away from said second side wall and toward the auxiliary rail thereby partially to open the box; an elongated pusher bar; and means mounting the bar in the frame transversely of the rails for movement in a circuitous path longitudinally forwardly through the outlet of the passageway between the upper and lower rails for engaging the rearwardly disposed corner and the second end wall of said partially open box further to unfold the box and to move the first side wall into engagement with the auxiliary rail whereby the box is fully opened, continued movement of the bar forcing the lever into retracted position to release the box for slidable movement forwardly of the wedges in the passageway, the bar returning rearwardly longitudinally outside of the passageway.

4. In a machine for opening a box of foldable sheet material having opposite side and end walls interconnected in rectangular relation along fold lines defining corners and having upper and lower side and end flaps respectively connected to the side and end walls but not connected to each other, the box being unfoldable from a flat condition folded along the fold lines of diagonally related corners to provide substantially coplanar first side and end walls and flaps and substantially coplanar second side and end walls and flaps in opposed relation to said first walls and flaps to an open substantially rectangular unfolded condition; an elongated support frame having forward and rearward end portions; an elongated

upstanding box guiding plate longitudinally mounted in the rear end portion of the frame having upper and lower edges and an elongated substantially horizontal slot therein intermediate said edges; vertically spaced substantially horizontal elongated main upper and lower flap engaging rails mounted in the forward end portion of the frame in laterally spaced substantially parallel offset relation to the plate, the upper rail having a rear end portion in closely adjacent opposed forwardly overlapping relation to the plate; an auxiliary substantially horizontal lower elongated box engaging rail in transversely spaced parallel relation to the main lower rail, the main and auxiliary rails and the guide plate defining an elongated box passageway having a narrow rear box feeding inlet between said end portion of the upper rail and the guide plate and a relatively wide forward outlet between the main and auxiliary rails; a substantially horizontal box supporting panel mounted in the frame beneath the lower rails and the passageway; substantially horizontal slide means mounted in the frame adjacent to the lower edge of the guiding plate in substantially coplanar relation with the panel and adjacent to the inlet of the passageway for supporting a folded box in upstanding position laterally adjacent to the plate with said first end and side walls and flaps facing the plate; means mounted in the frame engageable with said second end and side walls and flaps of such box for yieldably urging it against the plate into alignment with said inlet; spaced upper and lower substantially vertically aligned wedges supported by the frame and extended into the outlet of the passageway substantially in the plane of the inlet; a box impeding lever supported by the frame for horizontal pivotal movement between a position extended into the passageway in forwardly spaced relation to the wedges and a position retracted out of the passageway; means connected to the lever yieldably urging it into said extended position; an endless box feeding chain; means mounting the chain for circuitous travel in a substantially horizontal plane coincident with the slot in the plate; a box feeding dog secured to the chain for movement therewith through the slot for engagement with the rearwardly disposed corner of such folded box to slide the box through said inlet and between the wedges and the main rails so that the wedges initially engage and bend said first end flaps outwardly of the passageway so that the wedges slide under said first side flaps into engagement with said second side flaps upon continued movement of the dog, further travel of the dog sliding the box forwardly in the outlet of the passageway until the forwardly disposed corner of the box strikes the lever whereby forward movement of the box is temporarily impeded, still further travel of the dog moving the end walls and said first side wall outwardly away from said second side wall and toward the auxiliary rail thereby partially to open the box; an elongated pusher bar; and means mounting the bar in the frame transversely of the rails for movement in a circuitous path longitudinally forwardly through the outlet of the passageway between the upper and lower rails for engaging the rearwardly disposed corner and the second end wall of said partially open box further to unfold the box and to move the first side wall into engagement with the auxiliary rail whereby the box is fully opened, continued movement of the bar forcing the lever into retracted position to release the box for slidable movement forwardly of the wedges in the passageway, the bar returning rearwardly longitudinally outside of the passageway.

5. In a machine for opening a box of foldable sheet material having opposite side and end walls interconnected in rectangular relation along fold lines defining corners and having upper and lower side and end flaps respectively connected to the side and end walls but not connected to each other, the box being unfoldable from a flat condition folded along the fold lines of diagonally related corners to provide substantially coplanar first side and end walls and flaps and substantially coplanar second side and end walls and flaps in opposed relation to said first walls and flaps to an open substantially rectangular unfolded condition; an elongated support frame having forward and rearward end portions; an elongated

and end walls and flaps and substantially coplanar second side and end walls and flaps in opposed relation to said first walls and flaps to an open substantially rectangular unfolded condition; an elongated support frame having forward and rearward end portions; an elongated upstanding box guiding plate longitudinally mounted in the rear end portion of the frame having upper and lower edges and an elongated substantially horizontal slot therein intermediate said edges; vertically spaced substantially horizontal elongated main upper and lower flap engaging rails mounted in the forward end portion of the frame in laterally spaced substantially parallel offset relation to the plate, the upper rail having a rear end portion in closely adjacent opposed forwardly overlapping relation to the plate; an auxiliary substantially horizontal lower elongated box engaging rail in transversely spaced parallel relation to the main lower rail, the main and auxiliary rails and the guide plate defining an elongated box passageway having a narrow rear box feeding inlet between said end portion of the upper rail and the guide plate and a relatively wide forward outlet between the main and auxiliary rails; means mounted in the frame for yieldably urging a folded box against the guiding plate with said first end and side walls and flaps against the plate; spaced upper and lower substantially vertically aligned wedges supported by the frame and extended into the outlet of the passageway substantially in the plane of the inlet; a box impeding lever supported by the frame for horizontal pivotal movement between a position extended into the passageway in forwardly spaced relation to the wedges and a position retracted out of the passageway; means connected to the lever yieldably urging it into said extended position; feeding means mounted in the frame for circuitous travel in a substantially horizontal plane coincident with the slot in the plate and extended through the slot for engagement with the rearwardly disposed corner of such folded box to slide the box through said inlet and between the wedges and the main rails so that the wedges initially engage and bend said first end flaps outwardly of the passageway so that the wedges slide under said first side flaps into engagement with said second side flaps upon continued movement of said feeding means, further travel of said feeding means sliding the box forwardly in the outlet of the passageway until the forwardly disposed corner of the box strikes the lever whereby forward movement of the box is temporarily impeded, still further travel of said feeding means moving the end walls and said first side wall outwardly away from said second side wall and toward the auxiliary rail thereby partially to open the box; and box pushing means mounted in the frame transversely of the rails for movement in a circuitous path longitudinally forwardly through the outlet of the passageway between the upper and lower rails for engaging the rearwardly disposed corner and the second end wall of said partially open box further to unfold the box and to move the first side wall into engagement with the auxiliary rail whereby the box is fully opened, continued movement of said pushing means forcing the lever into retracted position to release the box for slidable movement forwardly of the wedges in the passageway, said pushing means returning rearwardly longitudinally outside of the passageway.

6. In a machine for opening a box of foldable sheet material having opposite side and end walls interconnected in rectangular relation along fold lines defining corners and having upper and lower side and end flaps respectively connected to the side and end walls but not connected to each other, the box being unfoldable from a flat condition folded along the fold lines of diagonally related corners to provide substantially coplanar first side and end walls and flaps and substantially coplanar second side and end walls and flaps in opposed relation to said first walls and flaps to an open substantially rectangular unfolded condition; an elongated support frame having forward and rearward end portions; an elongated

box guiding plate mounted in the rear end portion of the frame having an elongated longitudinally extended slot therein; elongated transversely spaced main flap engaging rails mounted in the forward end portion of the frame and in a plane in substantially parallel offset relation to the plate, one of the rails having a rear end portion in closely adjacent opposed forwardly overlapping relation to the plate; an elongated auxiliary box engaging rail in transversely spaced parallel relation to the main rails and opposite thereto, the main and auxiliary rails and the guide plate defining an elongated box passageway having a narrow rear box feeding inlet between said end portion of the upper rail and the guide plate and a relatively wide forward outlet between the main and auxiliary rails; means mounted in the frame for yieldably urging a folded box against the guiding plate with said first end and side walls and flaps against the plate; transversely aligned wedges supported by the frame and extended into the outlet of the passageway substantially in the plane of the inlet and with the rails therebetween; a box impeding lever supported by the frame for pivotal movement between a position extended into the passageway in forwardly spaced relation to the wedges and a position retracted out of the passageway; means connected to the lever yieldably urging it into said extended position; feeding means mounted in the frame for circuitous travel in a plane coincident with the slot in the plate and extended through the slot for engagement with the rearwardly disposed corner of such folded box to slide the box through said inlet and between the wedges and the main rails so that the wedges initially engage and bend said first end flaps outwardly of the passageway and so that the wedges slide under said first side flaps into engagement with said second side flaps upon continued movement of said feeding means, further travel of said feeding means sliding the box forwardly in the outlet of the passageway until the forwardly disposed corner of the box strikes the lever whereby forward movement of the box is temporarily impeded, still further travel of said feeding means moving the end walls and said first side wall outwardly away from said second side wall and toward the auxiliary rail thereby partially to open the box; and box pushing means mounted in the frame transversely of the rails for movement in a circuitous path longitudinally forwardly through the outlet of the passageway between the main rails for engaging the rearwardly disposed corner and the second end wall of said partially open box further to unfold the box and to move the first side wall into engagement with the auxiliary rail whereby the box is fully opened, continued movement of said pushing means forcing the lever into retracted position to release the box for slidable movement forwardly of the wedges in the passageway, said pushing means returning rearwardly longitudinally outside of the passageway.

7. In a machine for opening a box of foldable sheet material having opposite side and end walls interconnected in rectangular relation along fold lines defining corners of the box, the box being openable from a flat condition folded along the fold lines of diagonally related corners to an unfolded substantially rectangular open condition; a support; and an elongated guide member rigidly mounted in the support and providing a longitudinally extended guiding surface; the combination of an elongated upright guide plate rigidly mounted in the support in laterally spaced, substantially parallel, overlapping relation to said guiding surface and having an elongated, longitudinally extended slot therein; a substantially horizontal sprocket mounted in the frame in laterally spaced relation to the guiding member, in the plane of the slot and for rotation about an upright axis; a chain in mesh with the sprockets; a feeding dog connected to the chain and movable therewith in a circuitous path about said upright axis for extension through the slot to engage the rear corner of a folded box positioned against the plate and to slide the box between the plate and the guiding member into a predetermined holding position against

the guiding member, the dog being thence movable transversely away from the member along the periphery of the sprocket, and return to the slot; means mounted on the guiding member engageable with the side wall of the folded box which is in direct contact with the member in said holding position to limit forward travel of the box and to prevent movement of said engaged side wall outwardly of the member whereby movement of the dog transversely away from the guiding member partially opens the box.

8. In a machine for opening a box of foldable sheet material having opposite side and end walls interconnected in rectangular relation along fold lines defining corners of the box, the box being openable from a flat condition folded along the fold lines of diagonally related corners to an unfolded substantially rectangular open condition; a support; elongated guide means mounted in the support and providing a support surface in a predetermined plane, said guide means providing forward and rearward end portions; means mounted in the support for holding one side wall of a flat folded box against said support surface and thereby preventing movement of said one side wall relative to the guide means, but with the other side wall and the end walls being free to pivot relatively forwardly into unfolded condition, and whereby the free walls provide a front corner and a rear corner; the combination of a box engaging dog; means mounting the dog in the support for movement about a predetermined axis in a circuitous path initially longitudinally of and in opposed substantially parallel relation to said surface in a forward direction for engagement with the rear corner of such a box held against said surface and thence transversely forwardly away from said surface to move said rear corner in a forwardly arcuate path partially to unfold said box, thence rearwardly out of box engagement, and return; a box pusher; and means mounting the pusher in the support for movement from a position rearwardly of that part of the path of the dog where the dog moves transversely forwardly away from said surface, and thence longitudinally forwardly of and in opposed substantially parallel relation to said surface for engaging said rear corner of the partially unfolded box to move said free walls into completely unfolded condition.

9. The machine of claim 8 including powered drive means having driving connection to both the dog mounting means and the pusher mounting means for respectively motivating the dog and the pusher in their respective paths of travel and in timed relation so that the pusher engages the rear corner of the partially unfolded box immediately subsequent to disengagement of said rear corner by the dog.

10. In a machine for opening a box of foldable sheet material having opposite side and end walls interconnected in rectangular relation along fold lines defining corners of the box and having upper and lower side and end flaps respectively connected to the side and end walls but not connected to each other, the box being openable from a flat condition folded along fold lines of diagonally related corners to an unfolded substantially rectangular open condition; a support; elongated upper and lower guide rails rigidly mounted in the support in vertically spaced relation to each other and having elongated, longitudinally extended edges lying in a common vertical plane, said rails having predetermined opposite front and rear end portions; a guide plate rigidly mounted in the frame having a side in spaced substantially parallel relation to the plane of said edges with the plate partially overlapping the rear end portion of one of the rails; means borne by the support for sliding a folded box between the plate and the rails along a path extended longitudinally of the rails and into a predetermined unfolding position with one side wall in juxtaposition to said edges of the rails, said diagonally related corners being disposed forwardly and rearwardly relative to each other along the rail; upper and lower wedges

individually mounted on the support above and below the upper and lower rails, respectively, for horizontal pivotal movement about a common vertical axis laterally spaced from said plane on the same side thereof as said plate and between positions extended transversely of said path of travel of a folded box for engagement by the forwardly disposed corner of such a box and positions retracted from said extended positions to permit sliding of the forwardly disposed corner of the box between the wedges and the rails, the wedges having rearwardly extended apices adapted to slide between the forwardly disposed end and side wall flaps and thereby to enter the box into contact with the side flaps connected to said one side wall; and means interconnecting the wedges and the support yieldably urging the wedges into said extended positions whereby said one side wall of the box is held against the rails while the other end and side walls are free to unfold outwardly from the rails.

11. The machine of claim 10 including box impeding means mounted in the support forwardly of the wedges for movement into and out of the path of travel of a folded box; means interconnecting said impeding means and support yieldably urging the impeding means into said path of travel; and a pusher mounted in the support for travel longitudinally forwardly of the rails in laterally spaced relation thereto for engagement with the rearwardly disposed corner of a folded box while said one side wall thereof is temporarily held in said box opening position by the wedges and the impeding means thereby to unfold the free end and side walls laterally outwardly of the rails and to bring the walls of the box into open condition, said pusher thereafter engaging the rearwardly disposed end wall of the open box and sliding the box forwardly past said impeding means and sliding said one wall outwardly from between the rails and the wedges.

12. In a machine for opening a box of foldable sheet material having opposite side and end walls interconnected in rectangular relation along fold lines defining corners of the box and having upper and lower side and end flaps respectively connected to the side and end walls but not connected to each other, the box being openable from a flat condition folded along fold lines of diagonally related corners to an unfolded substantially rectangular open condition; a support; elongated guide means rigidly mounted in the support having upper and lower edges, an elongated, longitudinally extended guiding surface disposed in a substantially vertical plane, and predetermined opposite front and rear end portions; means borne by the support for sliding a folded box along a path extended longitudinally of the surface of the guiding member and into a predetermined unfolding position with one side wall in juxtaposition to said guiding surface, said diagonally related corners being disposed forwardly and rearwardly relative to each other along said surface; upper and lower wedges individually mounted on the support above and below the guide means, respectively, for horizontal pivotal movement about a common vertical axis offset from and extended transversely of said surface, said wedges being pivoted between positions extended transversely of said path of travel of a folded box for engagement by the forwardly disposed corner of such a box and positions retracted from said extended positions to permit sliding of the forwardly disposed corner of the box between the wedges and the guide means, the wedges having rearwardly extended apices adapted to slide between the forwardly disposed end and side wall flaps and thereby to enter the box into contact with the side flaps connected to said one side wall; means interconnecting the wedges and the support yieldably urging the wedges into said extended positions whereby said one side wall of the box is held against the guide means while the other end and side walls are free to unfold outwardly from the rails; and a pusher mounted in the support on the same side of the guide

means as said axis for movement longitudinally of the guiding surface from a position rearwardly of the wedges to engage the rearwardly disposed corner of such a folded box to move said free walls outwardly from the held wall to a position forwardly of the wedges to slide 5 a box opened by the pusher longitudinally of the guide means.
